UNITED STATES PATENT OFFICE.

FRANK E. CALLAHAN AND JAMES J. CALLAHAN, OF CLEVELAND, OHIO.

GRAB-BUCKET.

1,117,549.

Specification of Letters Patent. Patented Nov. 17, 1914.

Application filed February 17, 1913. Serial No. 748,909.

To all whom it may concern:

Be it known that we, FRANK E. CALLAHAN and JAMES J. CALLAHAN, citizens of the United States, residing at Cleveland, in the 5 county of Cuyahoga and State of Ohio, have invented a certain new and useful Improvement in Grab-Buckets, of which the following is a full, clear, and exact description, reference being had to the accompanying drawings.

This invention relates to grab buckets of the clam-shell type, such as are commonly used in excavating and in the handling of coal, ore, and other such materials, and 15 which comprise, generally, two jaws which are pivoted at their inner ends to a beam and which are connected at their outer ends, by means of arms or links, to a head, the beam being supported from said head by block 20 and tackle whereby the beam is lowered and raised to cause the opening and closing of the jaws of the bucket. To the heads of such buckets are applied the supporting means, the upper block of the tackle, a guide for the 25 closing cable- or chain, and the upper ends of the links which support the outer ends of the bucket jaws. In consequence of these facts, the head of the bucket is subjected to constant wear at the various points of the 30 aforesaid connections, the wearing action being increased by the presence of sand and grit between the engaging surfaces of the parts, such conditions being prevalent in work of the nature wherein these buckets 35 are employed. This makes it necessary to occasionally replace the head in order to obtain a satisfactory operation of the bucket, and this we have found, by experience, to be an expensive and inconvenient practice.

40 It is the object of this invention, therefore, to provide a head for grab buckets which is composed of a major head-piece to which may be rigidly secured the various minor parts which are subjected to wear, and 45 to make these wearing parts durable, simple and cheap of production, and to construct the major head-piece in a manner that will permit said minor pieces to be replaced easily and quickly.

50 The above and further objects we attain by a construction set forth in the claims annexed hereto and illustrated in the accompanying drawings forming a part hereof, wherein Figure 1 is a side elevation of a grab bucket embodying our invention; and Fig. 2, 55 an end elevation thereof.

In the drawings, 1 represents the jaws of the bucket which are provided, at their upper, inner corners, with hinge members 2 by means of which the jaws are pivoted to the beam 3. To the outer corners of the jaws are riveted, or otherwise secured, castings 4, the lower ends of which are made angular to fit the corners and to provide flanges through which rivets or other securing means may pass, while the upper ends of said castings are provided with ears 5. Between the ears of each of the castings 4 is pivoted the lower end of one of the arms or links 6 which suspend the outer ends of the jaws 1 from the head of the bucket.

The upper ends of the arms or links 6 terminate in eyes which encircle the end portions of the head shaft 7 and are held thereon by washers and cotter pins 8 and 9 respectively. Fixed upon the head shaft, intermediate of the portions which accommodate the aforesaid eyes, is a casting which will be referred to hereinafter as the major head-piece. The major head-piece comprises a cylindrical body portion 10 which is provided, near its ends, with annular flanges 11. Spaced inwardly a slight distance from the flanges 11 are lugs 12 which are rectangular in plan and which project upwardly from the body portion 10 of the head-piece. Projecting from the front and rear sides of the body portion 10, and in a plane other than at right angles to the longitudinal axis thereof, are ears 13. These ears extend slightly above and below the body portion 10 and have rounded corners which are provided with bolt holes. Extending in the same direction from the body portion 10, and in a parallel plane with the ears 13, are ears 14. 90 These ears extend outwardly and downwardly and have rounded ends provided with bolt holes which are in alignment with the bolt holes in the lower corners of the ears 13.

100 The spaces between the ears 13 and 14 are of a width equal to the thickness of the sheave-plates 15. The upper edges of the sheave-plates 15 are curved inwardly to conform to the lower surface of the body portion 10 of the head-piece, and on either side of this curved portion the plates are provided with bolt holes which are adapted to register with the bolt holes in the ears 13—14 when the upper corners of the plates occupy 105 the spaces therebetween, or bear upon the outer surfaces of the ears 14. The outer 110

edges of the sheave-plates 15 diverge downwardly to where they join the lower edges in rounded corners provided with bolt holes for the accommodation of the bolts 16. These 5 bolts pass through all of the plates and carry spacers which separate and properly position the plates along the bolts. Between the plates 15 are contained the upper portions of the sheaves 17 which are journaled upon 10 the shaft 18 mounted within openings in the various plates. Sheave-plates 20 are secured to the upper ends of the ears 13 by bolts 21. Between these plates is journaled the supporting sheave 22.

15 Secured to the sides of one of the lugs 12, by bolts 25, are angle bars 26. These bars project a sufficient distance beyond the end of the lug 12 to accommodate the grooved rollers 27. Cylindrical rollers 28 are journaled between the L-shaped brackets 29, the 20 horizontal flanges of which are bolted to the corresponding flanges of the angle bars 26, the rollers 28 being somewhat longer than the distance between the centers of the 25 grooved rollers 27. This provides a guard and guide for the closing cable.

From the description thus far, it will be seen that we have produced a head construction for grab buckets wherein the wear 30 is confined to parts which may be cheaply produced and easily replaced and which comprises, besides these minor parts, a major head-piece to which these parts may be rigidly secured, and which is practically 35 indestructible, no wear whatever falling thereupon.

Located centrally upon the beam 3 is a block 30 which is substantially pear shaped in cross section as shown in dotted lines in 40 Fig. 1. This block is positioned upon the beam 3 by the sleeves 31, the inner ends of which engage the ends of said block and the outer ends of which bear against the inner hinge members 2. The ends of the 45 beams are threaded for the reception of nuts 32 which are locked in place by the cotter pins 34. The upper portion of the block 30 is provided with a longitudinal bolt hole for the bolt 35 which secures the 50 lower ends of the sheave-plates 36 within transverse cuts formed in the upper portion of the block 30. These sheave-plates, with the sheaves 37 which are mounted therebetween, provide the lower block for 55 the block and tackle.

From Fig. 2 it will be seen that the closing cable 40 is secured at 41 to the body

portion 10 of the bucket head between one of the flanges 11 and the adjacent lug 12, and after passing down and around the 60 first sheave 37 of the lower block, it passes directly vertical to the first sheave 17 of the upper block, and because of the angular disposition of this sheave with respect to the axis of the bucket head, the cable 40 65 is cast downwardly in the plane of the second sheave of the lower block. Passing around this sheave the cable is directed upwardly over the center sheave of the upper block which advances the cable to the plane 70 of the next lower sheave, and after passing therearound and over the last of the upper sheaves it is directed about the last sheave of the lower block whence it passes upwardly between the grooved rollers 27 and 75 the cylindrical rollers 28 of the cable guide to the boom or other supporting structure.

Having thus described our invention, what we claim is:—

1. As a new article of manufacture, a 80 major head-piece for buckets of the character set forth comprising a cylindrical body portion having a plurality of vertical ears extending laterally and downwardly therefrom at other than right angles to the longitudinal axis of the head, certain of said ears being elongated vertically to provide means for the rigid attachment of, and for spacing apart, the plates of the bucket supporting sheave, the downwardly projecting 90 ears spacing apart and rigidly supporting the plates of a plurality of sheaves.

2. As a new article of manufacture, a major head-piece for buckets of the character set forth comprising a cylindrical body 95 portion having a series of vertical ears projecting downwardly and outwardly from the opposite sides thereof at other than right angles to its longitudinal axis, the corresponding ears of both series being in alignment and all of the ears being parallel to each other, and one ear of one series and the corresponding ear of the other series being elongated vertically, as and for the purpose specified.

In testimony whereof, we hereunto affix our signatures in the presence of two witnesses.

FRANK E. CALLAHAN.
JAMES J. CALLAHAN.
